UNITED STATES PATENT OFFICE.

BENJIMAN P. SCHNEIDER, OF NORFOLK, NEBRASKA, ASSIGNOR OF ONE-HALF TO
JOHN B. FITZGERALD, OF NORFOLK, NEBRASKA.

ELECTRIC MESSAGE-CARRIER.

1,115,339.

Specification of Letters Patent.

Patented Oct. 27, 1914.

Application filed September 16, 1913. Serial No. 790,092.

To all whom it may concern:

Be it known that I, BENJIMAN P. SCHNEIDER, a citizen of the United States, residing at Norfolk, in the county of Madison and 5 State of Nebraska, have invented new and useful Improvements in Electric Message-Carriers, of which the following is a specification.

This invention relates to improvements in 10 store service systems, and has particular application to a system whereby cash, packages and other articles may be transferred from one place to another.

In carrying out the present invention it is 15 my purpose to provide a system of the class described wherein the carriage bearing the article carrier will be electrically propelled and automatically brought to a stand-still upon reaching the limit of its path of travel.

20 It is also my purpose to provide a store service system wherein the current of the electrically propelled traveling carriage will be automatically cut off and the carriage held against further movement upon reaching 25 the limit of its path of travel and wherein in the carriage will be released and the flow of the current through the motor reversed immediately succeeding the release of the carriage thereby permitting the latter to 30 travel in the reverse direction.

Further I aim to provide a system of the type set forth which will embrace the features of simplicity, efficiency and durability and one which may be installed and maintained at a minimum expense.

With the above objects in view and others of a like nature, the invention consists in the construction, combination and arrangement of parts hereinafter set forth in and 40 falling within the scope of the appended claim.

In the accompanying drawings:—Figure 1 is a view in elevation of a store service system constructed in accordance with my present invention; Fig. 2 is a view in side elevation of the carriage showing the same on an enlarged scale; Fig. 3 is a top plan view of the system; Fig. 4 is an enlarged perspective view of a part of the same; Fig. 5 is a transverse horizontal sectional view 45 through the motor, showing the reverser in one position; Fig. 6 is a similar view, showing the reverser in neutral position; and Fig. 7 is a view in side elevation of the car-

riage equipped with a modified form of carrier.

Referring now to the accompanying drawings in detail, numerals 1—1 designate conductors spaced apart in parallelism and composed of any suitable material capable of 60 conducting an electric current. Each conductor has one end thereof suitably fastened to and insulated from a screw shank 2 passed through an aperture in a plate 3 suspended from a suitable support through the 65 medium of a screw-bolt 4 uprising from the upper edge of the plate 3. These screw shanks 2 pass loosely through the respective apertures and are spaced apart horizontally in parallel relation so as to accommodate the 70 conductors 1—1 and have their free extremities thereof equipped with thumb nuts 5 whereby the screw shanks may be moved within the respective openings or apertures in the plate 3 to put the conductors under 75 more or less tension. The opposite extremities of the conductors 1—1 are appropriately fastened to and designed to be wrapped about a shaft 6 journaled in horizontally alining bearings 7 carried by lugs 8 extending 80 outwardly from one face of a plate 9 and suitably spaced apart, the conductors 1—1 being insulated from the shaft 6. Uprising from the top edge of the plate 9 is a screw bolt which is designed to be passed 85 through a support so that the plate 9 may be suspended and equipped with suitable lock-nuts. One end of the shaft 6 terminates in a non-circular extension 11 designed to receive a handle, wrench or the like so that 90 the shaft 6 may be rotated within its bearings and the conductors tightened or slackened, as desired. In order to hold the shaft 6 against backward rotation subsequent to placing the conductors 11 under tension any 95 suitable means may be employed. In the present instance, a ratchet wheel 12 is keyed upon one end of the shaft 6 and is normally engaged by a spring-pressed dog 13 pivoted upon the adjacent edge of the plate 9. 100

The numerals 14—14 designate blocks disposed between the conductors 1—1 in proximity to the plates 3 and 9. Each block is equipped at the opposite sides thereof with outwardly-projecting lugs 105 15—15 formed with horizontal bores parallel with the sides of the block and receiving insulating bushings 16, through which

the conductors 1—1 pass. Thus, the blocks 14—14 are supported by the conductors 1—1 and capable of sliding movement thereon. Suitably connected to the rear 5 edge of each block 14 adjacent to the upper end thereof and extending rearwardly therefrom is a rod 17 passed through an aperture formed in the adjacent plate near the upper edge thereof and formed at its 10 rear end with screw threads 18 to receive a nut 19. Interposed between the confronting surfaces of the block and the respective plate is a relatively heavy coiled expansion spring 20 encircling the respective 15 portion of the rod 17, while surrounding the remaining portion of the rod is a light expansion spring 21 acting in opposition to the spring 20 and having one end in engagement with the adjacent face of the 20 plate, and the opposite end abutting the nut 19. By means of this construction, it will be seen that should either one of the blocks 14—14 be subjected to an impact, such block will slide along the conductors 1—1 toward the adjacent plate 3, 9, and against the action of the respective spring 20, thereby cushioning the shock or jar. Succeeding this movement of the block, the spring 20 re-acts to return the 25 block to normal position, while the spring 21 counter-acts the action of the spring 20 to a certain extent thereby preventing the sudden return of the block to normal. Extending downwardly and forwardly from 30 each block 14 is a horn 22 terminating a suitable distance below the plane of the conductors and equipped at one side edge with a holding lug 23 and at the opposite edge with an ear 24 formed with an aperture 35 receiving the screw shank 25 of an obstacle 26.

Designed to travel upon the conductors 1—1 is an electrically propelled carriage 27 composed, in the present instance, of a 40 metallic frame 28 suspended between the conductors 1—1 from axles 29—29 journaled in the opposite ends of the frame and having fast upon the opposite ends thereof wheels 30 formed with peripheral grooves 45 to engage the conductors 1—1. Mounted within the frame 28 and suitably fastened thereto is an electric motor 31 of the reversible type. The conductors 1—1 are adapted to be connected up to a suitable 50 source of electric energy by means of wires 32, while the wheels upon one of the axles 29 act as current collectors and have fastened to the inner faces thereof, concentrically of the axle, annular bands 29', upon 55 which bear brushes 29^a connected with the motor leads 29^b so that when the conductors 1—1 are energized, the current may be directed through the motor by way of the respective train of wheels 30, the bands, the 60 brushes and the leads. Connected in cir-

cuit with the motor is a reverser comprising, in this instance, annular series of segments 33' having the confronting ends thereof spaced apart or otherwise insulated from one another and adapted to be bridged 70 by means of bridging strips 34—34 carried by a block 35 at diametrically opposite points rotatably mounted upon a pin 36 disposed centrally of the segments. This reverser is suspended from the under side 75 of the motor and is supported thereby, and connected to the block 35 is a horizontal lever 37 having one end thereof pivotally connected to a rod 38 mounted for sliding movement within apertures 39—39 formed 80 in the opposite side walls of the frame 28 and having the axes thereof mounted in parallelism with the conductors 1—1, so that the rod 38 is similarly located. Mounted within alining slots 40—40, formed 85 in the side walls of the frame 29 and disposed at the side of the reverser opposite from the openings 39—39, is a holding bar 41 having the opposite ends thereof formed with down-turned lugs 42—42 adapted to 90 engage one or the other of the holding lugs 23 and the central portion thereof curved upwardly, as at 43, so that the lever 37 may be swung about its fulcrum before engaging the bar 41. Between the side walls 95 of the frame the bar is provided with outwardly extending pins 44 whereby accidental displacement of the bar from the frame is avoided.

In practice, the shaft 6 is rotated, as previously described, to place the conductors 1—1 under the desired tension and the conductors connected up with the source of current. Assuming the carriage to be traveling in the direction of the arrow as indicated 100 in Fig. 1, the lug 42 on the forward end of the bar 41 will, upon the carriage reaching the limit of the path of travel, ride upon the holding lug 23 on the horn 22 of the respective block 14 and engage such lug 110 so as to hold the carriage against further movement. Simultaneously with the lug 42 riding upon the lug 23, the respective end of the bar 38 abuts the obstacle 26 and so swings the lever 37 from the position shown 115 in Fig. 5 to that illustrated in Fig. 6, thereby cutting off the flow of current to the motor. When it is desired to release the carriage and reverse the travel thereof the lever 37 is swung about its fulcrum to the position opposite from that shown in Fig. 5 whereby the flow of current to the motor is reversed and the respective end of the bar 41 elevated to relieve the lug 42 of the influence of the holding lug 23. Thus, the 120 carriage may travel along the conductors 1—1 toward the opposite ends thereof.

In the form of my invention illustrated in Figs. 1 to 6, inclusive, the lower end of the frame 28 is equipped with a depending an-

- nular flange 45 formed at diametrically opposite points with bayonet slots 46 adapted to receive pins 47 extending outwardly from a cup 48 designed to receive coins. 5 This cup carries a spring-pressed lever 49 normally engaging the bottom of the cup and adapted to clamp bills in place. Thus, coins and bills may be transmitted from place to place.
- 10 In the form of my invention illustrated in Fig. 7, the carrier is in the form of a basket 50 suitably fastened to the lower end of the frame 28 and designed to convey packages.
- 15 From the foregoing description, taken in connection with the accompanying drawings, the construction, mode of operation and manner of employing my invention will be readily apparent. It will be seen that I provide a store service system wherein the 20 electric current of the motor of the carriage is automatically cut off and the carriage held against movement when the same reaches the limit of its path of travel. Furthermore, it will be noted that when the reversing lever 37 is swung about its fulcrum so as to reverse the motor, such lever will engage one of the heels formed at the juncture of the bend or curved portion 43 with the main body portion of the bar 41, so as to elevate 25 the respective end of the holding bar, thereby relieving the carriage of the influence of the holding lug succeeding the reversing of the motor.
- 30 While I have herein shown and described one embodiment of the invention by way of illustration, I wish it to be understood that I do not confine myself to the precise details of construction herein described and delineated, as modification and variation 35 may be made within the scope of the claims
- and without departing from the spirit of the invention. Furthermore, it is to be understood that my invention in its useful application is not limited to store service systems, as the same may be employed in connection with other conveying apparatus. 45
- Having thus described my invention, what I claim is:
- 50 In a store service system, a pair of conductors spaced apart in parallelism and adapted to be connected up with a source of current, blocks at the opposite ends of said conductors, a horn depending from each block, a stop lug at the lower end of said horn upon one side thereof, an abutment lug 55 upon the other side of said horn, a carriage mounted upon said conductors and adapted to travel along the same, an electric motor on said carriage and receiving current from said conductors, a reverser and circuit 60 breaker on the carriage connected in circuit with said motor, a rod capable of sliding movement and having the opposite ends thereof adapted to engage said abutment lugs when the carriage reaches the limit of 65 its path of movement in one direction or the other, a connection between said rod and reverser and circuit breaker whereby the flow of current to the motor will be cut off upon the carriage reaching the limit of its path 70 of movement, and means on said carriage adapted to be engaged by said stop lug to hold the carriage against movement succeeding the cutting off of the current.
- 75 In testimony whereof I affix my signature in presence of two witnesses.
